UNITED STATES PATENT OFFICE.

ALPHEUS W. ALTORFER, OF ROANOKE, ILLINOIS, ASSIGNOR TO POWER WASHING MACHINE CO., OF PEORIA, ILLINOIS, A CORPORATION OF ILLINOIS.

DRIVING MECHANISM AND SUPPORT THEREFOR.

1,047,118.

Specification of Letters Patent.

Patented Dec. 10, 1912.

Application filed December 17, 1909. Serial No. 533,666.

To all whom it may concern:

Be it known that I, ALPHEUS W. ALTORFER, a citizen of the United States, residing at Roanoke, in the county of Woodford and State of Illinois, have invented certain new and useful Improvements in Driving Mechanism and Supports Therefor; and I do hereby declare that the following is a full, clear, and exact description of the invention, which will enable others skilled in the art to which it appertains to make and use the same.

This invention has reference to a combined driving mechanism for a wringer and a washing machine, and has for its object to provide an apparatus capable of containing or supporting, both a wringer and a washing machine, and having a power mechanism for driving a washing machine independently of or simultaneously with the wringer.

The principal object of this invention is to provide a machine frame or support adapted to hold a washing machine and having movably mounted thereon a supplemental supporting frame adapted to sustain a wringer mechanism, whereby the latter may be moved to different positions on said frame or support, the purpose being to operate the wringer to wring clothes from the washing machine directly into a rinsing tub and from there into a basket or other receptacle, all being placed on said frame or support, and the washer and wringer mechanisms being driven by power.

The invention has for a further object to provide an apparatus of the character described, having power mechanism for driving a washing machine and a wringer; said mechanism associated with clutch devices, whereby the wringer may be intermittently connected with the power, and manually operated means for controlling the clutch device from opposite sides of the apparatus.

A further object of the invention, is to provide an apparatus supporting a movable frame to which may be attached a wringer; power devices; means for intermittently connecting the power with the wringer in different positions, and power devices for operating a washing machine.

The entire apparatus is so constructed that a washing machine may be supported on the same and the wringer moved into

proximity thereto, whereby the clothes may be put into the wringer direct from the washing machine and when wrung deposited in a tub which may also be supported on said apparatus.

A further object of this invention is the provision of a main frame adapted to support a washing machine, having a supplemental frame adapted to support a wringer mechanism and movably mounted on said main frame, said supplemental frame being mounted on supporting members or runners which slide on said main frame and having a power member connecting said supporting members or runners, and clutch devices movable with said supplemental frame for operatively connecting said wringer mechanism to the main shaft.

That the invention may be more fully understood reference is had to the accompanying drawings, in which

Figure 1 is a side elevation of my improved driving mechanism, and the apparatus supporting the same, and showing a washing machine, wringer and tub in dotted lines in their respective positions on the apparatus, when in use; Fig. 2 is an end elevation looking at the right hand end of Fig. 1; also showing in dotted lines the position of the driving wheel of the washing machine when disconnected; Fig. 3 is a cross-section as the same would appear if taken on the line 3—3 of Fig. 1, looking in the direction of the arrow in said figure; Fig. 4 is an enlarged detail in plan of certain clutch parts, and Fig. 5 is a side view of Fig. 4.

Like numerals of reference indicate corresponding parts throughout the figures.

In the drawings the numeral 1 designates the machine support or main frame preferably rectangular in form and having the longitudinal side members 1, the end members 2, and the end supporting members or legs 3.

Extending longitudinally of the frame, and preferably located adjacent to and upon the outside of one of the side pieces 1, is a driving shaft 4 which is journaled in suitable bearings 5 attached or secured to said side member. On one end of this shaft are carried pulleys 6 and 7. The latter is the driving pulley for the shaft 4 and said pulley may receive its power in any suitable

manner and from any suitable source, and while I have shown said pulley 7 as a single pulley, it is of course understood that it may comprise a fast and a loose member on the shaft, with means for shifting the belt or other driving means. The pulley 6 is used for transmitting power from the shaft 4 to the power mechanism of a washing machine, in a manner which I shall now explain.

A washing machine, which I have designated as A, and which may be of any approved construction, so long as it has a driving wheel B carried on an operating shaft C, may be seated within the frame of the apparatus, in manner shown, or supported directly on the frame of said apparatus.

To operate the wheel B of the machine, a belt 8 is employed, driven by pulley 6, and said belt travels cross-wise of the apparatus and around an idler pulley 9 carried by a bar 10 pivotally attached at 11 to the end member 2. A spring 12 which is attached at one end to the bar 10 and has its other end attached to the frame maintains the belt 8 in position for frictionally engaging and operating said wheel B of the washing machine. Should it be found that this mode of driving was not satisfactory, a second idler wheel 13 shown in dotted lines in Fig. 2, may be employed, which said wheel is carried by a bar 14, also shown in dotted lines in Fig. 2, which is secured to the frame.

In Fig. 2 the wheel B is in contact with the belt 8, and in dotted lines it is shown how the same may be raised from engagement with the belt to cut off the power from the washing machine. In connection with said apparatus, I provide a supplemental frame for supporting a wringer mechanism, which supplemental frame is so mounted as to be movable on said main frame to position said wringer at various positions relative to the washing machine supported on one end of said main frame. This supplemental frame is preferably slidable on the main frame and comprises spaced uprights or standards and a head or top piece connected thereto on which the wringer mechanism is mounted. These uprights or standards are preferably positioned on opposite sides of said main frame and are supported on supporting members or runners which are slidable on said side members 2 of the main frame. Suitable driving mechanism is provided for said wringer including clutch devices slidable with said supplemental frame on said shaft 4 and which may be clutched thereto at any position of said supplemental frame. These runners are connected by a brace member which extends beneath said side members and supports the actuating means for said clutch devices. A

detailed description of this construction follows.

Slidable longitudinally on the upper edges of the side members 1 of the main frame are the oppositely disposed supporting members 70 or runners 15, which are connected by the brace, bar or plate 16 extending down along side the side members 1 and then transversely across the main frame beneath the side members. The supporting members or 75 runners support the supplemental supporting frame which comprises the spaced standards or uprights 17 and the top or head piece 18, these members constituting the support for the wringer D, of any well known or approved construction, which may be attached or clamped thereto in any suitable manner. To one of the rolls of said wringer is connected shaft E which carries a pulley 19 or other suitable driving 80 member which is operated through the following connections.

The shaft 4 is preferably provided for a portion of its length with a groove or key-way 20, see Figs. 4 and 5, and carried on the shaft and having a key fitting said key-way is a slidable clutch member 21; also slidably carried but loose on said shaft 4 is a driving member in the form of a pulley or sheave wheel 22, having a clutch face 23, 95 adapted to have a clutch engagement with clutch member 21. This driving member is permanently operatively connected with the wringer mechanism to drive the same and this connection is preferably made as follows. The pulley or sheave wheel 22 drives a belt 24 and said belt is carried around and operates the sheave wheel 19 of the wringer. To keep the belt 24 taut, it is passed over an idler 25 carried by an arm 26, 100 adjustably attached to one of the uprights 17 of said supplemental frame. The supporting members or runners and the supplemental frame may be moved longitudinally of the side members 1 by grasping the uprights 17, but preferably by grasping either end of a rocking bar or operating lever 27 extending transversely and beneath the frame of the apparatus and having hand-holds 28 on its opposite ends. The rocking 110 bar or operating lever 27 passes through brackets or bearings 29 secured to the under side of the brace, bar or plate 16, and on the side of the apparatus to which is attached the shaft 4, said bar or operating 115 lever passes up between the shaft 4 and vertical portion of brace, bar or plate 16 and cross-wise of and engaging the clutch member 21 in manner seen in Fig. 5. It will thus be seen that an operator, when on 120 either side of the apparatus, may by grasping the hand-hold 28 of bar or operating lever 27 move the supporting members or runners 15, brace, bar or plate 16 and supplemental frame length-wise of the appa- 130

5 ratus and by rocking said bar or operating lever 27 may cause the clutch member 21 to engage or be disengaged from the clutch face 23 of the pulley or sheave wheel 22. When moving the supplemental frame from the left to the right looking at Fig. 1, the clutch member 21 bearing against the clutch face of the pulley or sheave wheel 22 will move said pulley along on the shaft, but to move the pulley 22, when the supplemental frame is moved from the right to the left of the apparatus, looking at Fig. 1, I provide the plate 30 attached to the brace, bar or plate 16, and said plate 30 has portions bearing across shaft 4 and against the pulley 22 which will move said pulley, in the direction just indicated.

With a washing machine contained in or supported on the frame of the apparatus, as shown in Fig. 1, the wringer mechanism on the supplemental frame may be moved to a position adjacent the washing machine, so that the clothes may be taken from the washing machine and passed through the wringer. If so, then a tub, designated as F, containing rinse water, may be supported on the opposite end of the frame, to receive the clothes, then the wringer and supplemental frame may be moved to the extreme left end of the apparatus and the clothes again passed through the wringer and deposited in a basket G, or other suitable receptacle. The supplemental frame being an open frame, it is readily seen that it may be passed over the tub F. With the clutch parts 21 and 23 arranged as shown the wringer may be operated at will in several different positions on the apparatus, and simultaneously with or independently of the washing machine.

Having thus fully described my invention, what I claim and desire to secure by Letters Patent of the United States, is,—

1. In a machine of the character described, in combination, a main frame, a supplemental frame mounted on said main frame, said supplemental frame including spaced uprights or standards positioned on opposite sides of said main frame, a head piece connected to said uprights or standards, a shaft journaled on said main frame and adapted to be driven from a suitable source of power, a driving mechanism at the head end of said supplemental frame, a driving member at the base of said supplemental frame, a permanent driving connection between said driving mechanism and said driving member, means for intermittently connecting said driving member with said shaft, said supplemental frame being so mounted on said frame support that the supplemental frame may be moved to position the driving mechanism on the supplemental frame in different positions relative to said frame support, and the driving con-

nnections between the driving mechanism and said driving member being so arranged that the movement of the supplemental frame will not disturb the permanent relation of said driving connection.

2. In a machine of the character described, in combination, a main frame, a supplemental frame mounted on said main frame, said supplemental frame including spaced uprights or standards positioned on opposite sides of said main frame, a head piece connected to said uprights or standards, a shaft journaled on said main frame and adapted to be driven from a suitable source of power, a driving mechanism at the head end of said supplemental frame, a driving member at the base of said supplemental frame and adjacent the lower end of one of its uprights or standards, a belt connection between said driving mechanism and said driving member, means for intermittently connecting said driving member with said shaft, said supplemental frame being so mounted on said frame support that the supplemental frame may be moved to position the driving mechanism on the supplemental frame in different positions relative to said frame support, and the belt connection between the driving mechanism and said driving member being so arranged that the movement of the supplemental frame will not disturb the relation of said belt connection.

3. In a machine of the character described, in combination, a main frame, a supplemental frame mounted on said main frame, said supplemental frame including spaced uprights or standards positioned on opposite sides of said main frame, a head piece connected to said uprights or standards, a shaft journaled on said main frame and adapted to be driven from a suitable source of power, a driving mechanism at the head end of said supplemental frame, a driving member at the base of said supplemental frame, a permanent driving connection between said driving mechanism and said driving member, clutch devices for operatively connecting said driving member with said shaft, means for controlling said clutch devices, said supplemental frame being so mounted on said frame support that the supplemental frame may be moved to position the driving mechanism on the supplemental frame in different positions relative to said frame support, and the driving connections between the driving mechanism and said driving member being so arranged that the movement of the supplemental frame will not disturb the permanent relation of said driving connection.

4. In a machine of the character described, in combination, a main frame, a shaft journaled in said frame and adapted to be driven from a suitable source of power, a

supplemental frame including spaced uprights or standards and a head or top piece connected thereto, a mechanism mounted on said supplemental frame, a driving member 5 adapted to be operatively connected with said shaft, a permanent connection between said driving member and said mechanism, clutch devices for connecting said driving member to said shaft, a lever arranged for 10 operating said clutch devices, said clutch devices, driving member and lever arrangement being movable with said supplemental frame.

5. In a machine of the character described, 15 in combination, a main frame, a shaft journaled in said frame and adapted to be driven from a suitable source of power, a supplemental frame including spaced uprights or standards and a head or top piece 20 connected thereto, a mechanism mounted on said supplemental frame, a driving member loosely mounted on said shaft, a permanent connection between said driving member and said mechanism, a clutch member slidably keyed to said shaft and adapted to operatively connect said driving member to 25 said shaft, said driving member and clutch-member being movable with said supplemental frame.

30 6. In a machine of the character described, in combination, a main frame, a shaft journaled in said frame and adapted to be driven from a suitable source of power, a supplemental frame including spaced uprights or standards and a head or top piece 35 connected thereto, a mechanism mounted on said supplemental frame, a driving member loosely mounted on said shaft, a permanent connection between said driving member and said mechanism, a clutch member slidably keyed to said shaft and adapted to operatively connect said driving member to 40 said shaft, a lever arrangement for operating said clutch member, said driving member, clutch member and lever arrangement being movable with said supplemental frame.

45 7. In a machine of the character described, in combination, a main frame, a shaft journaled in said frame and adapted to be driven from a suitable source of power, a supplemental frame including spaced uprights or standards and a head or top piece 50 connected thereto, a mechanism mounted on said supplemental frame, said shaft being provided with a groove or keyway, a driving member loosely mounted on said shaft, permanent connections between said driving member and said mechanism, a clutch member slidably keyed in said groove or 55 keyway in said shaft and adapted to operatively connect said driving member to said shaft, and means for operating said clutch member, said driving member, clutch member and operating means being movable 60 with said supplemental frame.

8. In a machine of the character described, in combination, a main frame, a shaft journaled in said frame and adapted to be driven from a suitable source of power, a supplemental frame including spaced uprights or standards and a head or top piece 65 connected thereto, a mechanism mounted on said supplemental frame, said shaft being provided with a groove or keyway, a driving pulley loosely mounted on said shaft and provided with a clutch face, a clutch member having a clutch face corresponding to the clutch face on said driving pulley and slidably keyed in said groove or keyway, means for operating said clutch member to 70 connect said driving member to said shaft, a belt operatively connecting said pulley and said mechanism, said driving pulley, clutch member and operating means being movable with said supplemental frame.

9. In a machine of the character described, in combination, a main frame, a shaft journaled thereon, said shaft having a groove or keyway formed therein, a supplemental frame slidably mounted on said main frame 90 and a mechanism on said supplemental frame, a pulley loosely slideable on said shaft and having an operative connection with said mechanism, said pulley having a clutch face, a clutch member slidably keyed to said shaft and having a clutch face corresponding to said clutch face on the pulley, and a plate member adapted to move with said sliding frame and bear against said pulley to move said pulley along the shaft in one 95 direction when the supplemental frame is moved, said clutch member serving to move the pulley along the operating shaft in the other direction when the sliding frame is moved.

10. A machine or frame support including longitudinal side members and end supporting members, a supplemental frame movably mounted on said support or frame and comprising oppositely disposed uprights or standards, a head or top piece connected thereto, supporting members or runners engaging and movable along said side members, said supporting members or runners supporting said uprights or standards, and a bottom brace or connecting member connecting said runners below said side members.

11. In a machine of the character described, in combination, a main frame, a shaft journaled therein, a supplemental frame including spaced uprights or standards, a head or top piece connected thereto, a mechanism on said supplemental frame, said supplemental frame being movable on said main frame, a driving member movable on said shaft, driving connections between said driving member and said mechanism, means for clutching said driving member in operative relation to said shaft and means 120

on said supplemental frame for moving said driving member and said clutching means therewith along on said shaft.

12. In a machine of the character described, in combination, a main frame including longitudinal side members, a supplemental frame mounted on said main frame and including spaced uprights or standards and a head or top piece connected thereto, supporting members or runners engaging and movable along said side members and supporting said spaced uprights and a bar or member connecting said runners and extending transversely of said frame beneath said side members.

13. In a machine of the character described, in combination, a main frame including longitudinal side members, a shaft journaled on said main frame, a supplemental frame mounted on said main frame and including spaced uprights or standards and a head or top piece connected thereto, a mechanism on said supplemental frame, supporting members or runners engaging and movable along said side members and supporting said spaced uprights and a bar or member connecting said runners and extending transversely of said frame beneath said side members.

14. In a machine of the character described, in combination, a main frame including longitudinal side members, a shaft journaled on said main frame, a supplemental frame mounted on said main frame and including spaced uprights or standards and a head or top piece connected thereto, a mechanism mounted on said supplemental frame, supporting members or runners engaging and movable along said side members and supporting said spaced uprights, clutch devices slidably along said shaft, connections between said clutch devices and said mechanism, and means on one of said supporting members or runners adapted to engage said clutch devices whereby when said supplemental frame is moved along said main frame said clutch devices and connections will be moved therewith.

15. In a machine of the character described, in combination, a main frame including longitudinal side members, a shaft journaled on said main frame, a supplemental frame mounted on said main frame and including spaced uprights or standards and a head or top piece connected thereto, a mechanism mounted on said supplemental frame, supporting members or runners engaging and movable along said side members and supporting said spaced uprights, a bar or member connecting said runners, clutch devices slidably mounted on said shaft, connections between said clutch devices and said mechanism, means on one of said runners to engage said clutch devices and move the same along the shaft when

the supplemental frame is moved therewith, and means carried by said connecting bar or member to operate said clutch devices.

16. In a machine of the character described, in combination, a main frame including longitudinal side members, a shaft journaled on said main frame, a supplemental frame mounted on said main frame and including spaced uprights or standards and a head or top piece connected thereto, a mechanism mounted on said supplemental frame, supporting members or runners engaging and movable along said side members and supporting said spaced uprights, a bar or member connecting said runners, clutch devices slidably mounted on said shaft, connections between said clutch devices and said mechanism, means on one of said runners to engage said clutch devices and move the same along the shaft when the supplemental frame is moved therewith, and means carried by said connecting bar or member to operate said clutch devices, said means including a lever having one end formed to actuate said clutch devices and the other end formed for manipulation and located on the opposite side of the main frame.

17. In a machine of the character described, in combination, a main frame including longitudinal side members, a shaft journaled on said main frame and positioned along one side thereof, a supplemental frame mounted on said main frame and including spaced uprights or standards and a head or top piece connected thereto, a mechanism on said supplemental frame, supporting members or runners engaging and movable along said side members and supporting said spaced uprights, clutch devices movable along said shaft, connections between said clutch devices and said mechanism, and means movable with said supplemental frame to operate said clutch devices.

18. In a machine of the character described, in combination, a main frame including longitudinal side members, a shaft journaled on said main frame and positioned along one side thereof, a supplemental frame mounted on said main frame and including spaced uprights or standards and a head or top piece connected thereto, a mechanism on said supplemental frame, supporting members or runners engaging and movable along said side members and supporting said spaced uprights, a bar or member connecting said runners and extending transversely of said frame beneath said side members, clutch devices slidably mounted on said shaft and movable with said supplemental frame, connections between said clutch devices and said mechanism, a lever mounted on said connecting bar or member and having one end posi-

- tioned to actuate said clutch devices and having the other end positioned on the opposite side of said frame for manipulation.
19. A machine support or frame, including longitudinal side members, end supporting members, and a floor or bottom mounted on said side members, a supplemental frame mounted on said machine support or frame, said supplemental frame including uprights or standards located at opposite sides of the machine support and a head piece connecting said uprights or standards, supporting members or runners, said uprights or standards being mounted thereon, said supporting members or runners being adapted to slide on said side members.
20. A machine support or frame, including longitudinal side members, end supporting members, a floor or bottom mounted on said side members, a supplemental frame mounted on said machine support or frame, said supplemental frame including uprights or standards located at opposite sides of the machine support and a head piece connecting said uprights or standards, supporting members or runners, said uprights or standards being mounted thereon, said supporting members or runners being provided with bearing means adapted to rest and move upon said side members.

21. A machine support or frame including longitudinal side members, end supporting members, a floor or bottom mounted on said side members, a supplemental frame mounted on said machine support or frame, 35 said supplemental frame including uprights or standards and a head piece connecting said uprights or standards, supporting members or runners, said uprights or standards being mounted thereon, said supporting 40 members or runners being adapted to slide on said side members, a brace member connecting said supporting members or runners below said bottom.

22. In an apparatus of the character described, in combination, a main frame, a shaft thereon, means for operating said shaft, a driving wheel on said shaft, an idler wheel mounted on said frame, flexible driving connections between said driving wheel 50 and idler wheel, driving mechanism slidably mounted on said frame, and means adapted to have a clutch connection with said shaft for actuating said driving mechanism.

In testimony whereof I affix my signature, 55 in presence of two witnesses.

ALPHEUS W. ALTORFER.
